UNITED STATES PATENT OFFICE.

IRVING F. NILES, OF PLAINFIELD, NEW JERSEY, ASSIGNOR TO R. HOE AND CO., OF NEW YORK, N. Y., A CORPORATION OF NEW YORK.

DELIVERY MECHANISM.

1,149,214.

Specification of Letters Patent. Patented Aug. 10, 1915.

Application filed May 3, 1912. Serial No. 694,686.

To all whom it may concern:

Be it known that I, IRVING F. NILES, a citizen of the United States, residing at Plainfield, county of Union, and State of New Jersey, have invented certain new and useful Improvements in Delivery Mechanisms, fully described and represented in the following specification and the accompanying drawings, forming a part of the same.

10 This invention relates to certain improvements in deliveries for printing machines.

The invention has for its object to produce an improved delivery mechanism for machines which print on sheets and in which 15 the sheets are delivered flat, said delivery mechanism being so constructed as to avoid smutting or blurring the sheets during the delivery operation.

With this and other objects not specifically referred to in view, the invention consists in certain constructions, and in certain parts, improvements and combinations as will be hereinafter fully described and then specifically pointed out.

25 Referring to the accompanying drawings Figure 1 represents the side elevation of the main elements of a printing press to which the improvement is applied; Fig. 2 is a plan view of the delivery mechanism constituting a part of the improvement; Fig. 3 is a side elevation showing a detail of the sheet carrier devices; Fig. 4 is a side elevation of a detail of a chain carrier; and Fig. 5 is an end elevation of the same.

30 Machines embodying the invention will include a printing couple one member at least of which is a cylinder. In the particular machine selected to illustrate the invention which is of the stop cylinder type, 35 the cylinder is indicated at 10 and the bed at 11. The operating mechanism for these parts may be of the usual type employed in stop cylinder machines and is not illustrated. The sheets are delivered to the cylinder, in the particular machine illustrated, 40 from a feed-board illustrated at 13. The flat delivery mechanism employed in machines embodying the invention will usually be of the fly type. The fly is indicated at 45 14 and delivers the sheets flat to a table, indicated at 15. The shaft of the fly is provided with a toothed segment 16 which is 50 operated in an obvious manner from a bent segment lever 17 through connections which 55 it is unnecessary to describe.

In machines embodying the invention the

construction will be such that the sheet is transferred from the cylinder to the fly delivery, and is presented to the fly with its freshly printed surface facing away from 60 the delivery, so that it will not be smutted or blurred by contact therewith. While this transferring mechanism may be varied, in the construction illustrated, it includes 65 the usual delivery cylinder 18 provided with grippers, as usual, which take the sheets from the grippers on the impression cylinder.

In the particular construction shown the sheets are delivered by the cylinder 18 to a conveyer which comprises (see Fig. 2) a 70 pair of horizontally disposed endless chains 19. These endless chains are shown as mounted on four sprocket wheels 20, 21, the wheels 20 being mounted on a shaft 22 and the wheels 21 on a shaft 23, these shafts being suitably supported in bearings arranged underneath the feed-board. The shaft 22 is driven from the cylinder 10 by means of a gear 50 on cylinder 10 meshing with a gear 51 on the delivery cylinder 18, which gear 80 in turn meshes with a gear 52 carried on the shaft 22. The chains support a cross shaft 24 and a cross rod 25, the shaft being mounted and the rod socketed in blocks 26 carried by the chains. The shaft supports a pair of gripper fingers 27 which coöperate with abutments 28 mounted on the rod 25. The gripper shaft is provided with a torsion spring 29 which serves to rock the shaft and hold the grippers closed, the shaft being 85 90 rocked to open the grippers by an arm 30 attached at one end of the shaft. This arm 30 is provided with an offset roller 31 which at the proper time, that is to say, when the grippers are to be opened, strikes an anchored arm 32 positioned on the shaft 22 before referred to. This arm not only opens the grippers 27 to release the sheet, as will be hereinafter referred to, but also causes the grippers to remain open, so that they 95 take the sheet from the grippers 33 on the delivery cylinder, these grippers being of the usual type. It will be understood that this delivery cylinder 18 is of the usual skeleton type, that is, it is made up of disks which are positioned so as to bear on the sheet at its center and margins only.

100 The transferring mechanism, in the particular machine illustrated, includes a sheet carrier which, as illustrated, comprises a 110 pair of tapes 34 arranged to run in a direction opposite to the run of the chains 19.

While this may be effected by any desired means, in the particular construction illustrated, the shaft 22 has a pair of loose pulleys 35 mounted thereon over which the tapes run, the tapes also running over a pair of pulleys 36 which are fast on the shaft 23. This shaft 23 may be driven in any suitable manner. As shown, it is provided with a sprocket wheel 37 over which runs a chain 38, this chain running over a sprocket wheel 39. This sprocket wheel is connected to a gear 40 meshing with a gear 41, this being one of the main gears of the machine. It will be observed that the tapes are so located that the upper run of the chains overlies the tapes. Stationary guides 42 are or may be provided to insure correct travel of the chains.

The operation of the mechanism will be clear from the description before given. The sheets are taken from the usual grippers on the impression cylinder by the grippers on the delivery cylinder 18 and by them delivered to the grippers 27 on the chain conveyor. The sheet is forwarded by the conveyor, the grippers of which hold it by its forward edge. After the grippers have completed their movement away from the cylinder 18 and during the time they are moving toward it, the lower edge and under side of the sheet is dragging across the carrier tapes, but as the freshly printed surface of the sheet is uppermost, the sheet is not blurred. As the grippers are completing their movement toward the cylinder 18, they are opened and the sheet drops onto the carrier tapes which immediately convey it over to and down upon the fly which is then operated to deposit the sheet on the table 15. The sheet may then be removed from this table by an attendant, or the usual slip sheets inserted to prevent offset against the following sheet.

Changes and variations may be made in the construction by which the invention is carried into effect. The invention claimed, therefore, is not to be confined to the particular construction described and illustrated in the accompanying drawings.

50. What is claimed is:—

1. The combination with a printing couple one member of which is a cylinder, of a flat sheet delivery, and means for transferring the sheets from the couple to the delivery, said means including a traveling conveyer constructed to hold the sheet by one edge and a carrier arranged to carry the sheets flatwise to which the conveyer delivers the sheet with its freshly printed side facing away from the carrier.

2. The combination with a printing couple one member of which is a cylinder, of a delivery cylinder for taking the sheets from the cylinder, a carrier arranged to carry the sheets flatwise, a traveling conveyer operating to transfer the sheets from the delivery cylinder to the carrier and to turn them over, so that their freshly printed surfaces will face away from the carrier, and a flat sheet delivery for receiving the sheets from the carrier.

3. The combination with a printing couple one member of which is a cylinder, of a carrier arranged to carry the sheets flatwise, a flat delivery for receiving the sheets directly from the carrier, and means including a traveling conveyer provided with a gripper mechanism for transferring the sheets from the cylinder to the carrier and delivering them thereto with their freshly printed surfaces facing away from the carrier.

4. The combination with a printing couple one member of which is a cylinder, of a flat delivery, a carrier arranged to carry the sheets flatwise, means including a traveling conveyer provided with grippers for transferring the sheets from the cylinder to the carrier, said conveyer moving in a path above the carrier, and means for driving the conveyer and carrier in opposite directions.

5. The combination with a printing couple one member of which is a cylinder, of a flat delivery, a set of carrying tapes delivering directly to the delivery, a set of parallel sprocket wheels and chains, a transverse shaft carried by the chains, grippers on the shaft, actuating means for the grippers, and means for driving the chains and tapes in different directions.

6. The combination with a printing couple one member of which is a cylinder, of a flat delivery, a feed-board for delivering sheets to the cylinder, a set of carrying tapes delivering directly to the delivery, said tapes being located under the feed-board, a set of parallel sprocket wheels and chains, said chains moving in a path above the tapes, a transverse shaft carried by the chains, grippers on the shaft, actuating means for the grippers, and means for driving the chains and tapes in different directions.

In testimony whereof, I have hereunto set my hand, in the presence of two subscribing witnesses.

IRVING F. NILES.
